TILE CLIP

Lou Harrington, San Antonio, Tex.

Application December 7, 1933, Serial No. 701,386

1 Claim. (Cl. 108—10)

The invention relates to method of laying Mission clay tiling, and particularly to the means for anchoring the cap tiles.

Heretofore in laying Mission tiling it has been the practice to first lay a course of the curved clay tiles with the concaved sides upward, the tiles being spaced laterally from one another, and secured to the roof sheathing by means of driven fastenings through holes provided in the tiles for this purpose. Another course of tile, known as cap tiles, is then laid covering the adjacent edges of the adjacent tiles, and these have been secured in position by means of blocks secured to the roof between the first mentioned tiles and extending high enough so that the cap tiles may be secured to the blocks by means of driven fastenings through the same holes as used in securing the first layer of tiles in place.

The invention has for its object the provision of a new method of securing the cap tiles in position by means of U-shaped anchors secured to the sheathing, and having outwardly directed terminals on the ends of the arms of the U-shaped member that engages through other holes in the tile provided for this purpose, said holes being spaced slightly from one end of the tile, that is the upper end, and at a slight distance from the side edges of the tile. This method not only securely holds the cap tiles in place, but is an advantage because the expense of laying the roof is reduced and the cap tiles are better held in position than with the old method.

The invention will be described in detail herein-after and will be found illustrative in the accompanying drawing, in which

Figure 1 is a fragmentary plan view of a portion of a Mission clay tiled roof in which the invention is disclosed.

Figure 2 is a sectional detail on a plane indicated by the line 2—2 of Figure 1.

Figure 3 is a transverse fragmentary sectional view on a plane indicated by the line 3—3 of Figure 1, and

Figure 4 is a plan view of one of the anchors used for securing the cap tiles in place.

In the drawing similar reference characters are used to designate corresponding parts in all the views.

The roof sheathing is indicated at A in Figures 1, 2, and 3, and the tiles are designated 10, and secured in place on the sheathing A by the method to be hereinafter described. The type of tile employed in this class of roof is what is known as Mission clay tiling, the tiles being transversely curved, and one layer is first laid on the sheathing

A, the tiles of the first layer being designated 10^a and have the concaved side up, and are secured in position by means of driven fastenings 11 through an opening 12 adjacent to the upper edge of the tile and midway of its width. The tiles 10^a of the first layer are spaced apart as shown at 13 in a horizontal direction, or in other words transversely of the pitch of the roof.

The cap tiles are designated 10^b and are laid to cover the adjacent edges of contiguous tiles of 10 the first layer with the convex side uppermost. The cap tiles 10^b are held in position by means of substantially U-shaped anchors 14. The anchors 14 are preferably made of a reasonably heavy gage of steel wire, cut into proper lengths, and each of 15 the lengths of wire is bent intermediate of its ends to form a loop 15 to receive a driven fastening 16 to secure the anchor in place. The ends of the wire at each side of the loop 15 are extended at an angle to one another as shown at 17 and then bent 20 as shown at 18 with the ends of the wire slightly inclined toward one another as shown at 19. The terminals of the portions 19 extend outwardly at substantially right angles to the parts 19 as shown at 20 to engage in openings 21, said openings being 25 adjacent to the upper edge of each tile and spaced at a slight distance from the side edges of the tile. When the anchor is in position as clearly shown in Figure 3 it is interposed between the tiles 10^a of the first layer and the tiles 10^b, the cap tiles. 30

In the drawing the opening 12 for the driven fastenings 11 is shown in the cap tile, and the openings 21 for the ends 20 of the anchor are shown in the bottom layer of tiles. It will be apparent that the opening 12 may be omitted 35 from each of the cap tiles, and in fact said openings 12 may be omitted from all of the tiles and the openings 21 used with the anchors 14 for the first layer if preferred.

What is claimed is:—

In a roof covering, in combination with roof sheathing, concave tiles laid on said sheathing with their concave sides uppermost in substantially parallel relationship and spaced from one another, other concave tiles bridging the spaces 45 between the first mentioned tiles and having their concave sides down, the edges of the last mentioned tiles overlapping the edges of the first mentioned tiles, the last mentioned tiles having openings in opposite sides thereof, U-shaped clips 50 having their extremities engaging in said openings and engaging between the overlapping edges of the tiles, and means securing said clips to the sheathing.

LOU HARRINGTON. 55
